UNITED STATES PATENT OFFICE.

HARRIET N. EWING, OF PHILADELPHIA, PENNSYLVANIA.

GAME APPARATUS.

SPECIFICATION forming part of Letters Patent No. 330,972, dated November 24, 1885.

Application filed September 24, 1885. Serial No. 177,972. (No model.)

To all whom it may concern:

Be it known that I, HARRIET N. EWING, a citizen of the United States, and a resident of the city and county of Philadelphia, and State 5 of Pennsylvania, have invented a new and useful Game Apparatus, of which the following is a specification.

The object of my invention is to furnish a game apparatus for children; and my invention consists in the combination, with a box divided into suitably marked or numbered compartments and furnished with a handle, of a cord one end of which is secured to the box or handle, and the other end of which is secured 15 to a ball or weight, and a post the top of which is furnished with a depression for holding the ball or weight.

The accompanying drawing, which forms part of this specification, is a perspective view 20 of my game apparatus, the sides of the box being broken away in places to more clearly illustrate its interior arrangement.

A is a box, which is divided by light strips into a number of compartments, *a*, which are 25 suitably marked by numbers, or by representations of flowers, birds, or animals. B is a handle secured to and projecting out from box A; C, a post within box A, the top of which is bored or hollowed out to form a depression, *b*. D is

a cord secured to the handle B or box A, and 30 E is a ball or weight secured to the free end of this cord.

In playing the game the ball or weight E is placed in the depression *b* in the top of post C and the handle B is grasped in the hand. By 35 a quick movement the ball or weight E is thrown from out the depression *b* into one of the compartments *a* of the box. The manner of counting is immaterial and can be arranged to suit the player or players. The weight E 40 may be thrown successively into each compartment, into the corner compartments only, into the numbered compartments, or into the compartments containing the representations of flowers or other objects.

Having thus described my invention, I claim and desire to secure by Letters Patent—

The combination of the box A, furnished with a handle, B, and divided into suitably marked compartments *a*, and post C, with a 50 depression, *b*, in its top, and cord D with weight E, all substantially as and for the purposes set forth.

HARRIET N. EWING.
